UNITED STATES PATENT OFFICE.

RUSSELL E. BENNER, OF DETROIT, MICHIGAN, ASSIGNOR TO BURROUGHS ADDING MACHINE COMPANY, OF DETROIT, MICHIGAN, A CORPORATION OF MICHIGAN.

DASH-POT.

1,150,925.

Specification of Letters Patent. Patented Aug. 24, 1915.

Application filed April 24, 1908. Serial No. 428,999.

To all whom it may concern:

Be it known that I, RUSSELL E. BENNER, a citizen of the United States, residing at Detroit, in the county of Wayne and State 5 of Michigan, have invented certain new and useful Improvements in Dash-Pots, of which the following is a specification.

My dashpot is particularly designed with reference to adding machines of the type 10 shown in Patents Nos. 504,963 and 505,078 in which a handle is drawn forward after the stops corresponding to the numerals to be registered have been set, and then released to complete the operation of the machine under the influence of a rather powerful spring. It is desirable that the forward 15 movement of the handle be made at a reasonable but limited speed and the reverse movement be made under less restriction for the most part but checked or slowed down as the handle approaches its normal position. The dashpot which forms the subject 20 matter of the present application is particularly adapted to accomplish this regulation of the movement of the adding machine parts though obviously it may be used in other connections where similar regulation is to be effected, and certain of its principles and features are applicable to dashpots in 25 general, as will appear more fully from the following detailed description of a preferred embodiment of the invention in connection with the drawings to which reference is made.

30 The accompanying drawings which form part of this specification illustrate a preferred form of embodiment of the present invention, Figure 1 representing a vertical section of the dash-pot with the piston at the end of its stroke; Fig. 2 representing a similar section of the dash-pot at an intermediate stage in the operation of the machine; Fig. 3 representing a fragmentary sectionalized elevation of the dash-pot, the 35 section being at right angles to that of Figs. 1 and 2; Fig. 4 representing a bottom plan view of the piston with the cylinder or shell in horizontal section; and Fig. 5 representing in perspective a plunger device detached.

40 In the accompanying drawings I have 45 illustrated my improved dashpot devices with the piston and cylinder shown with bearings for connection to the proper ele-

ments of an adding machine of the character described or other machine elements, the 55 relative movements of which are to be regulated thereby.

Referring now to Figs. 1 and 2 the reference numeral 847 designates the piston proper which occupies the bore of the shell 60 or cylinder 892 with sufficient clearance to provide for the latter's sliding back and forth over the sides of said piston. The latter is formed with longitudinal ports or 65 passage-ways *a* extending from top to bottom and opening at both ends, said ports being lined with soft metal bushings *b* which preferably project slightly above the upper surface of the piston for a purpose herein-after explained. The piston is formed with 70 a central elongated cylindrical portion 847^a open at the bottom and closed at the top and upwardly beyond this cylindrical portion extends a tubular part 847^b to which the stem 802 is joined. Within the cylindrical portion 847^a of the piston there slides 75 a plunger comprising a central piston-like part 830, fitting the large bore of the piston proper, a downwardly-projecting hollow stem or tubular part 830^a forming an oil 80 passage-way and an upwardly-projecting guide stem 830^b fitting the smaller bore of the piston extension 847^b, tubular for a distance in continuation of the lower stem and grooved in one side as at *c* to provide a permanent passage-way between the interior of the tubular extension 847^b of the piston and the interior of the cylinder 847^a. A spring 889 surrounds the stem 830^b bearing at one end against the upper end of the head of the 90 cylinder 847^a and at its other end against the central piston-like portion of the plunger, this spring thus tending to thrust the latter downwardly. A washer *d* confines the plunger, limiting its downward movement, 95 said washer being secured against a shoulder of the cylinder 847^a by headed screws *e* as shown in Figs. 3 and 4. The chamber of the cylinder 847^a communicates with the interior of the hollow stem 830^a through a 100 port *h* and the lower edge of said hollow stem is cross-grooved providing small notches *i* as most clearly seen in Fig. 5. On the exterior of the cylinder 847^a there is arranged to slide a sleeve 827 having at its 105 lower end a flange 827^a spaced from the

walls of the cylinder and adapted to close upon the upper ends of the port bushings *b* but having ports *f* alining with the ports *a* though of restricted diameter. The sleeve is prevented from turning by a pin *x* projecting upwardly from the piston (Fig. 3) and loosely engaging an opening in the flange *827^a*. Said sleeve has an upper flange *g* constituting a baffle plate. A nut *847^c*, screwing upon the tubular part *847^b* of the piston provides a shoulder to limit the upward movement of the sleeve *827*.

The operation of the dash-pot is as follows: Normally with the cylinder *892* elevated or the piston depressed according to which element is attached to the movable part the hollow stem *830^a* is in contact with the base of said cylinder and the spring *889* is compressed as shown in Fig. 1. The sleeve *827* is elevated at the conclusion of a return stroke of the piston but after a period of rest of the machine would settle upon the piston or the bushings *a*. At any rate downward movement of the cylinder *892* or upward movement of the piston immediately causes the said sleeve to lower relatively to the piston, bringing its flange *827^c* upon the upper ends of the bushings *b*, thus restricting the passage-ways to the diameter of the ports *f*. It will of course be understood that the cylinder *892* is charged with oil as indicated in the drawings and that as said cylinder lowers this oil finds its way through the ports *a* and *f*. With the lowering of the cylinder *892* its base separates from the plunger stem *830^a* and the spring *889* eventually thrusts the plunger *830* downward, so that at the end of the forward stroke the parts have assumed the relative positions illustrated in Fig. 2. It will be observed that the plunger *830* has taken up a position at the lower end of the cylinder *847^a*, the oil having entered freely through the tubular stem *830^b* and the port *h* as the plunger assumes that position under impulse of the spring *889*. It will be understood that there is ample space between the stem *830^a* and the washer *d* for the oil to pass through as said plunger thus moves outward or downward. Now as soon as the cylinder starts back the sleeve *827* is slid up on the cylinder *847^a* by the pressure of oil against its flanges *g* and *827^c*, the latter uncovering the ports *a* and thus permitting acceleration in the return movement of parts, both of said flanges being separated from the walls of the cylinder by ample spaces. But when the base of the cylinder *892* strikes the end of the hollow stem *830^a*, a marked retardation takes place for a quantity of oil is trapped in the chamber of the cylinder *847^a* and there is no escape except through the small notches *i*. Consequently the remaining return movement of parts is considerably slowed down and am-

ple time will be allowed for the transfer or carrying operations no matter how many are to take place successively. The downward movement of the cylinder or the upward movement of the piston is retarded only proportionally to the limitation of the flow of liquid through the piston by the ports *f* as compared to, the restriction of flow occasioned by the size of the ports *a* and such relative movement of the piston and cylinder is of course unaffected by the plunger within the chamber *847^a* though the latter when released by the upward movement of the piston relative to the cylinder shifts as above described. The upward movement of the cylinder with respect to the piston is even less restricted because of the movement of the ported sleeve *827* until the bottom of the cylinder comes in contact with the hollow stem *830^a* and therefore up to such point the relative movement of the parts is more rapid. The restriction for checking and cushioning is solely that affecting flow of oil out of the interior plunger-cylinder *847^a*, and the start downward of the exterior cylinder *892* is not resisted by any vacuum effect within said interior cylinder. The start downward of the exterior cylinder does not have to be accompanied by flow of oil to said interior cylinder through the restricted ports formed by the notches *i*. The exterior cylinder simply moves away from the notched stem and the oil flows to the interior cylinder freely thereafter as the spring *889* forces the plunger down. The projection of the bushings *b* above the upper surface of the piston *847* obviates suction which might result as the handle starts rearward, from contact of the flange *827^c* with so extended a surface as that presented by the upper side of said piston. It will be understood that the upper flange *g* serves to prevent the oil from shooting up through the ports *f* when the piston returns home and causing a spraying or foaming in the upper part of the cylinder.

While the construction here shown is well adapted to thoroughly fulfil the objects primarily stated yet it is to be understood that the invention may be carried out otherwise and the claims which follow are phrased accordingly.

What I claim is:

1. In a dashpot, the combination of a cylinder and a piston, there being provision for the passage of fluid from one side of the piston to the other, said piston being formed with a longitudinally extending chamber, a plunger movable in said chamber, there being communication between said chamber and the exterior thereof, said plunger adapted to be moved relatively to said chamber by contact with said cylinder.
2. In a dash-pot the combination with cylinder and piston, of an axially sliding mem-

ber carried by the piston and ported for the passage of the fluid, said member adapted to contact with the head of the cylinder at one end of the stroke with provisions for thereby restricting the fluid flow.

3. In a dash-pot the combination of an exterior cylinder, a ported and chambered piston, and a plunger in the chamber of the piston having a passage opening into the same and into the exterior cylinder and adapted to contact with the head of the latter at one end of the stroke with provisions for thereby restricting the fluid flow between the chamber and the cylinder.

15 4. In a dash-pot the combination of an exterior cylinder, a ported and chambered piston, and a plunger in the chamber of the piston having a passage opening into the same and into the exterior cylinder and adapted to contact with the head of the latter at one end of the stroke with provisions for thereby restricting the fluid flow between the chamber and the cylinder, the plunger being spring-loaded toward the head of the latter.

5. In a dash-pot, the combination of an exterior cylinder; a piston therein ported for the passage of fluid in either direction, said piston being cylindrically chambered; and a plunger comprising a piston-like portion fitting said chamber and a tubular stem projecting therefrom for contact with the head of the cylinder, said plunger being ported to provide for communication between the chamber and the interior of the tubular stem and the latter formed to cause restriction of fluid flow when in contact with the cylinder head.

6. In a dash-pot, the combination of an exterior cylinder; a piston therein ported for the passage of fluid in either direction, said piston being cylindrically chambered and bored; and a plunger comprising a central piston-like portion fitting the said chamber, a guiding stem engaging the bore of the piston proper, and a tubular stem projecting out of the chamber and adapted to contact with the head of the cylinder, said plunger being ported to provide for communication between the chamber and the interior of the tubular stem and the latter formed to cause restriction of fluid flow when in contact with the cylinder head.

7. In a dash-pot, the combination of an exterior cylinder; a piston therein ported for the passage of fluid in either direction, said piston being cylindrically chambered; a plunger comprising a piston-like portion fitting said chamber and a tubular stem projecting therefrom for contact with the head of the cylinder, said plunger being ported to provide for communication between the chamber and the interior of the tubular stem and the latter formed to cause restriction of fluid flow when in contact with the cylinder head.

head; and a spring forcing the plunger outwardly.

8. In a dash-pot, the combination of an exterior cylinder; a piston therein ported for the passage of fluid in either direction, 70 said piston being cylindrically chambered and bored; a plunger comprising a central piston-like portion fitting the said chamber, a guiding stem engaging the bore of the piston proper, and a tubular stem projecting out of the chamber and adapted to contact with the head of the cylinder, said plunger being ported to provide for communication between the chamber and the interior of the tubular stem and the latter 80 formed to cause restriction of fluid flow when in contact with the cylinder head; and a spring surrounding the guiding stem of the plunger and tending to force the latter outwardly.

9. In a dash-pot the combination with cylinder and piston, of a sliding tubular member carried by the piston and ported for the passage of the fluid, said tubular member adapted to contact with the head of 90 the cylinder at one end of the stroke and being notched to then permit restricted fluid flow.

10. In a dash-pot, the combination of an exterior cylinder; a piston therein ported 95 for the passage of fluid in either direction, said piston being cylindrically chambered; and a plunger comprising a piston-like portion fitting said chamber and a tubular stem projecting therefrom for contact with the 100 head of the cylinder, said plunger being ported to provide for communication between the chamber and the interior of the tubular stem and the latter notched to permit restricted fluid flow when in contact 105 with the cylinder head.

11. In a dash-pot, the combination of an exterior cylinder; a piston therein ported for the passage of fluid in either direction, said piston being cylindrically chambered; 110 a plunger comprising a piston-like portion fitting said chamber and a tubular stem projecting therefrom for contact with the head of the cylinder, said plunger being ported to provide for communication between the 115 chamber and the interior of the tubular stem and the latter notched to permit restricted fluid flow when in contact with the cylinder head; and a spring forcing the plunger outwardly.

12. In a dash-pot, the combination of an exterior cylinder, piston therein ported for fluid flow in either direction and a sliding sleeve on the piston flanged to cover the port or ports of the latter, and itself restrictively ported, said sleeve having a second flange extending over the port of the first-mentioned flange.

13. In a dashpot, the combination of an exterior cylinder, a piston therein ported for 130

4

fluid flow in either direction and having a raised portion encircling the port, and a sliding closure piece for the piston port adapted to seat against said raised portion 5 while separated from the surrounding surface of the piston, said closure itself being restrictedly ported in alignment therewith.

14. In a dash-pot the combination of an exterior cylinder, a ported and chambered 10 piston, a plunger in the chamber of the piston having a passage opening into the same and into the exterior cylinder and adapted to contact with the head of the latter at one end of the stroke with provisions for thereby 15 restricting the fluid flow between the chamber and the cylinder, and a sliding closure piece for the piston port itself restrictedly ported in alignment therewith.

15. In an appliance of the character described, the combination of means for uniformly retarding the stroke in one direction, means for permitting acceleration in the opposite direction throughout the greater portion of the stroke, and fluid operated means 20 for retarding and cushioning the latter stroke at its end, while eliminating suction or vacuum resistance at the commencement of the first-mentioned stroke.

16. In a dash-pot, a cylinder and piston, 30 the latter provided with a relatively movable member mounted in the piston and forming a chamber therewith, there being provision for the passage of liquid to and from said chamber and means for arresting 35 the movement of said movable member dur-

ing the latter portion of the movement of the piston.

17. In a dash-pot, a cylinder and piston provided with passages for fluid from one side of the piston to the other, means for throttling the flow of liquid in one direction only, a chamber in the piston, a plunger movable in the chamber, means for arresting the motion of the plunger as the piston nears the end of its stroke there being a passage from the chamber to the exterior of the piston and provision for throttling the passage when the plunger moves inward in the chamber.

18. In a dashpot, a cylinder and piston, the latter provided with a relatively movable member mounted in the piston and forming a chamber therewith and having a port therein for the passage of liquid to said chamber, and means for arresting the movement of said movable member during the latter portion of the movement of the piston and decreasing the flow of fluid through said port.

19. In a dashpot, the combination with the cylinder and piston, of an axially sliding member mounted in and closing a chamber in said piston and having a passage therethrough, said member adapted to come in contact with the head of the cylinder and thereby partially close said passage.
